UNITED STATES PATENT OFFICE.

JOHN A. THROP, OF THREE RIVERS, MICHIGAN.

PUMP-PISTON.

SPECIFICATION forming part of Letters Patent No. 252,066, dated January 10, 1882.

Application filed October 10, 1881. (No model.)

To all whom it may concern:

Be it known that I, JOHN A. THROP, a citizen of the United States, residing at Three Rivers, in the county of St. Joseph and State 5 of Michigan, have invented certain new and useful Improvements in Common Well-Pumps; and I do hereby declare the following to be a full, clear, and exact description of the invention, such as will enable others skilled in the 10 art to which it appertains to make and use the same, reference being had to the accompanying drawings, and to the letters or figures of reference marked thereon, which form a part of this specification.

15 My invention relates to improvements in common well-pumps; and it consists in an attachment to the sucker or plunger of a pump in the shape of an india-rubber sleeve or band fitted to and encircling the plunger, and held 20 in place by a number of teats or lugs on the inner side of the band, which fit into corresponding holes made in the outside of the wooden part of the plunger; and my invention further consists in surrounding the lower bucket of a 25 well-pump with a circular or annular rubber packing, having lugs similar to those above described on its inner surface, said lugs fitting into holes or openings in the outer surface of the bucket, for the purpose of making an air-tight joint and a perfect fit of the bucket to an 30 irregular or oblong hole in the pump-log.

In the drawings, wherein similar letters of 35 reference indicate like parts in the several figures, Figure 1 shows the plunger of a pump provided with my sleeve or band. Fig. 2 is a sectional view of the same with the side of the rubber band cut away to show the openings in the plunger and the lugs in the sleeve. Fig. 3 shows a section of a lower bucket provided 40 with an encircling rubber sleeve or band and having the staple or ring for removing the bucket from the pump-log, and also shows the thin disk-valve. Fig. 4 is a sectional view of the rubber packing.

45 I construct my plunger *b* in the usual manner, and of the customary materials, making a shoulder around the lower end to receive and hold the rubber sleeve *a*, which is annular in shape and slightly flaring at the top to fit the 50 general shape of the plunger, the upper edge being made thinner so, that it will readily bend inwardly and prevent "buckling," and pro-

jecting from the inside of the sleeve is a series of four or more lugs or teats, *f*, which fit closely in openings *c*, corresponding with them in size and depth, made in the plunger. As the rubber sleeve is made to fit closely to the plunger, considerable effort will be required to force it into place on the plunger, but when once in place the lugs will enter the openings made to receive them, and it will be impossible to accidentally displace it. If, however, it is desired to remove the rubber sleeve, it can be done with ease and without injury either to the sleeve or plunger.

65 In the old method of using leather or rubber packing, where the same was attached to the plunger by nails or tacks, it was impossible to remove the packing without injuring or destroying both the packing and the plunger.

70 Another advantage derived from the employment of my rubber sleeve is that the plunger is strengthened instead of weakened, and there is no liability of the band turning round, and thus working off the plunger, nor is there any 75 danger of buckling.

75 The lower bucket, *h*, (shown in Fig. 3,) is constructed with an encircling ring, of thick rubber, *i*, provided with lugs on the inner side to fit in cavities in the sides of the bucket, as do 80 the lugs of the sleeve in the holes in the outer surface of the plunger. This packing-ring, being very thick, makes an air-tight joint, and also where the hole in the pump log has become irregular from the unequal shrinking or 85 swelling of the same after boring, or from decay or unsoundness in the wood, or from any other cause, the packing-ring will adapt itself to the inequalities of the bore and still preserve an air-tight joint.

90 The ring or staple *k*, attached to the lower bucket, is for the purpose of removing the bucket from the pump without taking the pump log out from the well, and the shank of the ring passes through the center of the bucket, 95 and is secured thereto by a nut on the under side thereof, or in any equivalent manner. The shank of this ring *k* passes through the center of a circular disk, of thin rubber, leather, or some other flexible material, *l*, which rests upon the upper side of the bucket, is of equal size therewith, covers the openings therein for the passage of the water, and forms the valve, and this valve *l* is retained in position by the pas-

sage through its center of the shank of the ring *k*, while its flexibility admits of its edges rising and allowing the upward passage of the water through the openings in the bucket.

5 I am aware that rings or bands of india-rubber and its compounds have been applied to wooden plungers for pumps to form a packing, and therefore I do not claim such packing, broadly; but

10 What I do claim as my invention and discovery, and desire to have secured to me by Letters Patent, is—

15 1. The packing of the plunger of a pump, consisting of an encircling sleeve or band of india-rubber or its compounds, constructed with a series of lugs or teats on its inner side, the said lugs adapted to fit into a correspond-

ing series of openings in the outer surface of the plunger for the purpose of retaining the packing in place, substantially as described. 20

2. The combination, in a common well-pump, of the plunger *b*, and the encircling rubber band or sleeve *a*, the latter provided with a series of teats or lugs, *f*, arranged to fit into a corresponding series of openings, *c*, in the plunger 25 and retain the band or sleeve in place while the pump is being operated.

In testimony whereof I affix my signature in presence of two witnesses.

JOHN A. THROP.
